UNITED STATES PATENT OFFICE.

JOHN H. HAWLEY, OF NEW YORK, N. Y.

DESIGN FOR A BUTTON.

45,910.

Specification for Design.

Patented June 9, 1914.

Application filed March 31, 1914. Serial No. 828,633. Term of patent 3½ years.

To all whom it may concern:

Be it known that I, JOHN H. HAWLEY, a citizen of the United States, and a resident of the borough of Manhattan, city and State of New York, have invented a new, original, and ornamental Design for Buttons, of which the following is a specification.

My design is represented in the accompanying drawing in which:

Figure 1 is a plan view. Fig. 2 is a side view. Fig. 3 is a section on line 3—3 of Fig. 2 of the button illustrating my new design.

The design consists of the ornamental shape shown. A substantially cylindrical cavity is provided in the central portion of the top thereof. As shown the bottom and the sides of the cavity and the upper surface of the button within the boundary of a substantial circle concentric to, and surrounding the walls of the cavity, have a uniform color, which contrasts with the color of the remaining surface of the button.

This gives the appearance of a round spot on the center of the button. The round shape space surrounding the center of the upper surface of the button is uniform in color and the shade of the remaining surfaces of the button is variable, but its general appearance is much darker than that of the round spot.

I claim:

The ornamental design for a button as shown and described, or any colorable imitation thereof.

In testimony that I claim the foregoing as my own, I have hereto affixed my signature in the presence of two witnesses.

JOHN H. HAWLEY.

Witnesses:

JOHN J. RANAGAN,
AGNES C. O'CONNELL.
